No. 744,781.

PATENTED NOV. 24, 1903.

L. F. MILLS.

APPARATUS FOR DESTROYING VERMIN ON POULTRY, BIRDS, &c.

APPLICATION FILED AUG. 31, 1903.

NO. MODEL.

UNITED STATES PATENT OFFICE.

LUCIUS F. MILLS, OF IONIA, MICHIGAN.

APPARATUS FOR DESTROYING VERMIN ON POULTRY, BIRDS, &c.

SPECIFICATION forming part of Letters Patent No. 744,781, dated November 24, 1903.

Application filed August 31, 1903. Serial No. 171,314. (No model.)

To all whom it may concern:

Be it known that I, LUCIUS F. MILLS, a citizen of the United States, residing at Ionia, in the county of Ionia and State of Michigan, have invented certain new and useful Improvements in Apparatus for Destroying Vermin on Poultry, Birds, &c.; and I do hereby declare the following to be a full, clear, and exact description of the invention, such as will enable others skilled in the art to which it appertains to make and use the same.

My invention relates to an apparatus for destroying vermin on the bodies of live poultry, birds, &c., by applying an insecticide in such manner as to insure its permeating the body-feathers.

The objects of my invention are to provide an apparatus which requires no frame in order to keep it in an extended position, one which is simple in its construction, being light, strong, and economical to manufacture, adapted to be taken apart, collapsed, and done up into packages which may be transmitted through the mail at very little expense, and, furthermore, which consists in the construction and arrangement of its parts, which will be more fully hereinafter described, and definitely pointed out in the claims. I attain these objects by means of the mechanism herein described, and illustrated in the accompanying drawings, in which—

Figure 1 is a side view of my improved insect-destroyer, and Fig. 2 an end view thereof. Fig. 3 is a longitudinal vertical section of my improved insect-destroyer; and Fig. 4, a transverse vertical section of the same, taken on the line $\alpha\alpha$ of Fig. 3. Fig. 5 is an enlarged detail view of the adjustable and securing mechanism shown in part used in my improved device. Fig. 6 is a side view of a modified form of my improved insect-destroyer shown in broken sections.

Referring to the drawings, 1 indicates a ring, having a series of holes 1' perforated through it at right angles to its perpendicular breadth. Said holes 1' are arranged at regular intervals, as shown more particularly by the dowels 7, Figs. 2 and 4, which are somewhat larger than said holes 1', the purpose of which dowels 7 will more fully hereinafter appear.

2 is a head composed of a ring 3, having an internal flange 4 formed on the inner circumferential surface thereof, which internal flange 4 forms a shoulder against which a disk 5 bears, (to close the end,) and it is secured to said shoulder by tacks or any other suitable means. Countersunk in the ring 3, at its inner perpendicular surface, are a series of holes 6, the centers of which are in a horizontal alinement with the holes 1' in the ring 1, being directly opposite thereto.

7 indicates a series of dowels which are removably secured within the holes 6 in the head 2 by means of screws 8. At the opposite ends of the dowels 7 are ferrules 9, secured thereto, having one end of round long threaded lugs 9' secured within the ends of said dowels 7 and their opposite ends extending through the holes 1' in the ring 1 and adjustably secured by means of nuts 10 and 11.

12 is a cylindrical drum made of canvas or other suitable flexible material, which is secured at one end to the inner circumferential surface of the flanged head 2 by tacks or other suitable means. Said cylindrical drum 12 extends within and through the ring 1 a considerable distance, as shown in Fig. 3; and is secured to the inner circumferential surface 75 of the ring 1 by the same means as is used at the opposite end thereof, and it is held in a taut position by means of the dowels 7, ferrules 9, round long threaded lugs 9', and nuts 10 and 11.

In the inner circumferential surface of the ring 1 a concave groove 13 is formed which extends around its entire surface.

14 is a wire ring bent in the form of a circle, divided at one portion of the same, the ends of which have a small space between them, as at 20, in order that the outer surface of said wire ring 14 may be closely compressed against the inner surface of the cylindrical drum 12 and the concave groove 13 and secured by means of staples 12' or other suitable material. It also serves the purpose of preventing the insecticide used within the cylindrical drum 12 passing out and becoming wasted while the apparatus is being tilted to eject the fowls or birds therefrom after they have been treated. At one end of the cylindrical drum 12 and contiguous thereto are a series of eyelets 15, through which a

cord 16 is interlaced, which cord 16, in combination with the extended portion 17, comprising the collapsible door of the cylindrical drum 12, serves to close the end of the apparatus to confine the fowls or birds therein at a time when it is desired to give them a treatment. The purpose of the eyelets 15 is to allow a quick shutting and opening of the door in that there is less friction on the cord were not said eyelets used.

In Fig. 2 I have shown the end of the apparatus closed, the cord 16 being secured in a taut position by means of a spring 18, secured to the outer perpendicular surface of the ring 1. The purpose of said spring 18 is to form a quick fastener for the collapsible door, which door is quickly opened, the fowls opening said door by their own weight as the apparatus is tilted on end, the eyelets allowing the cord to easily slip through them in the operation, thus avoiding the handling of fowls after they have been treated.

Referring to Fig. 6, which is a modified form of my device, A indicates a head similar in form to the one shown in Figs. 1 and 4, having holes extending therethrough instead of being countersunk, as is shown in Fig. 3, and B a ring with holes extending therethrough, said holes in said head and ring being for the reception of the dowels a.

The dowels a are plain, being of one diameter only, there being no ferrules 9' attached, as shown in Figs. 1 and 3, nor are there any screws 8 for securing the dowels at one end, as is shown in Fig. 3, said dowels being adjustably secured by means of nuts b c and d e. The flexible drum 12 is secured by the same means as is shown in said Fig. 3.

The operation of the device is as follows: The cord 16 is removed from the spring 18, which will allow the end of the flexible door 17 to be opened either outward or inward, after which fowls or birds are put in, and a small quantity of insect-powder is distributed along the bottom inner surface of the cylindrical drum 12. The apparatus is then rotated forward and backward on a floor, the ground, or any other suitable place a few times until the insect-powder has become thoroughly mixed with the feathers, after which said apparatus is raised up at the end opposite the flexible door 17, which will allow the fowls or birds to be ejected by their own weight; but none of the powder used will necessarily come in contact with the person who is operating the device.

One of the most important features of my invention is its collapsibility. It can be taken apart for mailing or shipping by removing the screws 8, turning back the nuts 10 against the ferrules 9, and removing the nuts 11, which will allow the dowels 7 to be withdrawn from the ring 1 and head 2. Said ring 1 and head 2 are then brought together, which will allow the flexible cylindrical drum 12 to collapse. The dowels 7, being tied together, are wrapped with ordinary wrapping-paper and tied with

string, as well as the ring 1, head 2, and flexible cylindrical drum 12.

I do not wish to confine myself to the exact details of construction as shown in the drawings, but may use two rings with collapsible doors, one in each end of the apparatus, without departing from the nature and spirit of my invention.

Having thus described my invention, what I claim as new, and desire to secure by Letters Patent, is—

1. In a collapsible apparatus for applying an insecticide to the bodies of live fowl, birds, &c., the combination of a drum made of flexible material having a flanged head at one end of said drum, and a ring at its opposite end, to hold the drum in circular form, which drum has an opening in one end formed by said ring, closed by a collapsible door, with a series of dowels interposed between the head and ring to hold the drum in an extended and taut position, the apparatus being adapted to rotate on and near a floor, the ground, or any other suitable place, substantially as described.

2. In a collapsible apparatus for applying an insecticide to the bodies of live poultry, birds, &c., the combination of a drum made of flexible material having a flanged head secured to one end of said drum, with a series of countersunk holes in said head, and a ring at the opposite end of said drum, secured thereto, with a corresponding number of holes extending through said ring, having a spring secured thereto, with a collapsible door secured to said ring, having a series of eyelets in said door near its outer edge, and a cord interlaced through said eyelets, which cord is adapted to hold said door in a closed position by means of the spring secured to said ring, to confine the fowls or birds and loose insecticide within said apparatus, and a series of dowels with ferrules secured on one end, and round, long threaded lugs therein, which are adjustably and removably secured within the holes in said head and ring, by means substantially as described.

3. In an apparatus for applying an insecticide to the bodies of live fowl, birds, &c., the combination of a drum having a flanged head at one end of said drum, and a ring at its opposite end, which has a concave groove formed in the inner, circumferential surface of said ring, with a wire ring within said drum and concave groove, secured thereto, and a collapsible door secured to said ring, which collapsible door has a series of eyelets therein, with a cord interlaced therethrough, and means for securing said collapsible door, and holding said apparatus in an extended position, substantially as described.

4. As an article of manufacture, an apparatus for applying an insecticide to the bodies of live fowl, poultry, &c., comprising a drum made of flexible material having a flanged head secured to one end of said drum with a series of countersunk holes in said head, a

ring at the opposite end of said drum, secured thereto, which has a number of holes extending through said ring corresponding to those in said flanged head, a concave groove formed in the inner, circumferential surface of said ring, a wire ring within said drum and concave groove, secured thereto, a spring secured to one of the outer, perpendicular surfaces of said ring, at the outer end of said drum, a collapsible door secured to said ring having a series of eyelets in said door near its outer edge with a cord interlaced through said eye-

lets, and a series of dowels with ferrules secured on one end, and round, long threaded lugs therein, which are adjustably and removably secured within the holes in said head and ring, by means substantially as described. ¹⁵

In testimony whereof I affix my signature in presence of two witnesses.

LUCIUS F. MILLS.
